UNITED STATES PATENT OFFICE.

PAUL DIETRICH, OF WEBB CITY, OKLAHOMA.

COLLAR-BUSTER STRUCTURE.

Original application filed September 16, 1924, Serial No. 738,099. Divided and this application filed November 18, 1926. Serial No. 149,174.

The present invention relates to deep well tools and more particularly to a casing tool whereby the same may be cut when required, said tool being constructed to slip over the 5 main pipe passing through the casing thereby preventing the tool from sticking in the well and causing trouble when removing the casing.

The invention furthermore provides a tool 10 which will operate equally well upon being jarred upwardly or downwardly when cutting a collar to admit of the casing being removed in sections.

This application is a division of that filed 15 by me on September 16, 1924, Serial Number 738,099, now issued as Patent No. 1,628,533, for a combined collar buster and casing spear.

Other objects and advantages will be apparent and suggest themselves as the nature 20 of the invention is understood.

While the drawings illustrate an embodiment of the invention it is to be understood that in adapting the same to meet different conditions and requirements, various changes 25 in the form, proportion and minor details of construction may be resorted to without departing from the nature of the invention.

Referring to the accompanying drawings forming a part of the specification,

30 Figure 1 is a vertical central sectional view of a well tool embodying the invention, and

Figure 2 is a cross sectional view taken on the line 2-2 of Figure 1.

35 Corresponding and like parts are referred to in the following description and designated in both views of the drawing by like reference characters.

The numeral 10 designates the casing or 40 upper enlarged pipe section of an oil well and 11 the smaller pipe passing therethrough and this casing comprises sections which are coupled by means of a collar 12 threaded thereto.

45 The tool comprises a tubular body 13 having a shank 14 to which the jarring rod is adapted to be attached in a manner well understood and the opening 15 of the body is of a size to receive the smaller pipe 11 of 50 the well so that the tool may be slipped therover when lowered into the well for use as a collar buster by being jarred upwardly or downwardly. The opening 15 is disposed to

one side of the center of the body whereby to provide a thickened portion 16. 55

An opening 24 is formed in the thickened part 16. A slot 25 is formed in the outer side of the thickened part 16 and communicates with the opening 24 and is adapted to receive the outer end of a peg 26 and the active portion of a pivoted bit 27. 60

The bit 27 is pivoted at one end to the body 13 as by a removable element indicated at 28 and is reversible so that it may be arranged to incline outwardly and downwardly as indicated by the full lines in Figure 3 or upwardly and outwardly as designated by the dotted lines in said figure, the active end of the bit being tapered to a chisel edge so as to cut a collar 12 of the casing when 70 it is required to separate the latter into sections to facilitate its removal. A spring 29 normally urges the active end of the bit 27 outwardly so as to engage and cut the collar when the tool is jarred upwardly or 75 downwardly according to the arrangement of the bit and the adaptation of the tool to operate by an upward or a downward jar. The pivot pin 28 for the bit is removable and adapted to be inserted through an upper or 80 a lower opening 30 intersecting the opening 24. 85

It is to be noted that the bit 27 cannot assume a horizontal position when within the pipe 10 so that thrust of the tool in either 90 direction, according to the angle of the tool 27, will cause the latter to engage the element 12 and cut it.

What is claimed is:-

1. A well tool adapted to be lowered into 90 the casing and comprising a tubular body to slip over the inner pipe, the bore of said body being eccentric to provide a relatively thick portion, and means fitted to the said body at the said portion thereof whereby to 95 adapt the tool for use as a collar buster, the collar busting means being reversible to admit of operation of the tool either by an upward or a downward jar.

2. A well tool adapted to be lowered into 100 a well casing, comprising a tubular body to slip over a well tube in said casing, a cutting element carried by said body and incapable of assuming a horizontal position while within the casing, so that it will assume an 105 inclined position when moved and thus op-

eratively engage the casing and means removably fastening said cutting element to the tool to permit reversal thereof to enable operation of the tool either by an upward or 5 a downward jar.

3. A well tool adapted to be lowered into a well casing, comprising a tubular body to slip over a well tube in said casing, a cutting element carried by said body and incapable 10 of assuming a horizontal position while

within the casing so that it will assume an inclined position when moved and thus operatively engage the casing, said body having a slot, and said cutting element being removably pivoted at one end and within said slot 15 to permit reversal thereof to enable operation of the tool either by an upward or a downward jar.

In testimony whereof I affix my signature.

PAUL DIETRICH.
